US00D620953S

(12) **United States Design Patent**
Andre et al.

(10) **Patent No.:** **US D620,953 S**
(45) **Date of Patent:** ** *Aug. 3, 2010

(54) **MEDIA DEVICE**

(75) Inventors: **Bartley K. Andre**, Menlo Park, CA (US); **Daniel J. Coster**, San Francisco, CA (US); **Daniele De Iuliis**, San Francisco, CA (US); **Richard P. Howarth**, San Francisco, CA (US); **Jonathan P. Ive**, San Francisco, CA (US); **Steve Jobs**, Palo Alto, CA (US); **Duncan Robert Kerr**, San Francisco, CA (US); **Shin Nishibori**, San Francisco, CA (US); **Matthew Dean Rohrbach**, San Francisco, CA (US); **Douglas B. Satzger**, Menlo Park, CA (US); **Calvin Q. Seid**, Palo Alto, CA (US); **Christopher J. Stringer**, Portola Valley, CA (US); **Eugene Antony Whang**, San Francisco, CA (US); **Rico Zorkendorfer**, San Francisco, CA (US)

(73) Assignee: **Apple Inc.**, Cupertino, CA (US)

(**) Term: **14 Years**

(21) Appl. No.: **29/266,005**

(22) Filed: **Sep. 11, 2006**

(51) **LOC (9) Cl.** **14-03**

(52) **U.S. Cl.** **D14/496; D14/203.3**

(58) **Field of Classification Search** ..... **D14/496, D14/401, 435, 474, 483, 217, 137, 138, 160, D14/168; 345/156, 169, 173-179, 905; 715/727-729, 864; 710/1, 5, 8; 713/1, 600; 455/11, 1, 7, 73, 344-347, 93, 95; 370/342-344; 369/1, 2, 6, 12; 463/43-47; 273/148 B**

CLAIM

We claim the ornamental design for an media device, substantially as shown and described.

DESCRIPTION

FIG. 1 is a top perspective view of a media device showing our new design;

FIG. 2 is a top view thereof;

FIG. 3 is a bottom view thereof;

FIG. 4 is a front view thereof;

FIG. 5 is a rear view thereof;

FIG. 6 is a right side view thereof; and,

FIG. 7 is a left side view thereof.

The broken lines are environmental only and form no part of the claimed design.
